UNITED STATES PATENT OFFICE.

ARTHUR J. CHAMPAGNE, OF NEW YORK, N. Y., ASSIGNOR TO CHRISTIAN W. SCHILD-WACHTER, OF NEW YORK, N. Y.

DEMOUNTABLE TOP FOR MOTOR-VEHICLES.

1,274,854.

Specification of Letters Patent.

Patented Aug. 6, 1918.

Application filed February 29, 1916. Serial No. 81,136.

To all whom it may concern:

Be it known that I, ARTHUR J. CHAMPAGNE, a subject of the King of England, residing at New York, in the county of New York and State of New York, have invented certain new and useful Improvements in Demountable Tops for Motor-Vehicles; and I do hereby declare the following to be a full, clear, and exact description of the invention, such as will enable others skilled in the art to which it appertains to make and use the same.

This invention relates to improvements in tops for motor vehicles, and more particularly to such as are adapted to be demountable, and to change the character of the motor vehicle, as, for example, from a touring car to a limousine.

The object in view is the provision of means for locking an additional section on to a door of a motor vehicle in such a manner as to be easily and quickly removable and at the same time to remain as firmly in place during operation as if formed integral with the door.

With this and further objects in view, as will in part hereinafter become apparent and in part be stated, the invention comprises certain novel constructions, combinations and arrangements of parts as subsequently specified and claimed.

In the accompanying drawing:—

Figure 1 is a view in side elevation of a motor vehicle embodying the features of the present invention.

Fig. 2 is a similar view on an enlarged scale of one of the doors detached.

Fig. 3 is a fragmentary section taken on the plane indicated by line 3, 3 of Fig. 1, with the door omitted, parts being seen in elevation.

Fig. 4 is an enlarged detail, vertical section taken on the plane indicated by line 4, 4 of Fig. 1.

Fig. 5 is an enlarged detail elevation of a fragment of the door looking at one corner portion thereof from the inside, parts being broken away and parts being seen in section.

Figs. 6 and 7 are vertical sections taken on the planes indicated respectively by lines 6, 6 and 7, 7, of Fig. 5.

Fig. 7* is a horizontal section taken on the plane indicated by lines 7*, 7* of Fig. 7.

Fig. 8 is a fragmentary plan view of the upper edge portion of the door, with the additional section detached.

Fig. 9 is a section similar to Fig. 7 of a slightly modified embodiment.

Fig. 10 is a view similar to Fig. 5 of a further modified form of the invention.

Figs. 11 and 12 are vertical sections taken on the plane indicated respectively by lines 11, 11, and 12, 12, of Fig. 10.

Fig. 13 is a view similar to Fig. 8 of the structure seen in Fig. 11.

Referring to the drawing by numerals, 1 indicates the body of any ordinary motor vehicle, mounted on the upper edge of which is the top 2 of the permanent character. The top 2 includes permanent corner pieces 3, 3, which depend from the top and rest against and are secured to the upper edge of the body 1. The intermediate spaces between these corner portions 3 are occupied by windows. The side windows 6, 6 are slidingly mounted on beads 4, fixed to the upper edge of the body 1, each window being held in place by any appropriate latches 5, 5, engaging the fixed portion of the top 2 and the upper edge portion of the body 1.

Between the side windows 6 and between one of the side windows 6 and the front corner pieces 3 are arranged window like sections, supplementing and forming continuations of the doors 7, 7 of the vehicle. These window like supplemental sections for the doors 7 are indicated at 8, and each is made up in itself of a frame carrying a transparent plate, after the ordinary manner of a window and similar to windows 6, 6. Each section 8, however, is detachably connected to its respective door 7 in a manner enabling easy application and removal of the section, while at the same time being held rigidly and firmly in place during use in a manner insuring against looseness or rattling of the parts.

The method of connection of each section 8 to its door 7 is susceptible of some variation, but must possess, as its essential characteristic, capacity for retaining the section against rattling or becoming loose relative to the door. To accomplish this result in the most efficient manner, while employing a construction presenting neatness in appearance and finish, I employ the structure disclosed in detail in Figs. 5 to 7, inclusive, wherein the door 7 is seen as notched at its upper edge, there being one such notch at each upper corner, and a retaining plate 9 is secured in the notch by screws 10, 10. The plate 9 is notched at its exposed face as indicated at 11, and is recessed near its inner or embedded face, as indicated at 12. The notch 11 and recess 12 open upwardly and between the said notch and recess is arranged a section 13 of upstanding material having the form of a thickened and relatively deep bead. For purposes of identification, the part 13 will hereinafter be referred to as a lug, with the understanding that that term is to signify any equivalent of the part 13 seen in the drawing. A bifurcated plate 14 is fixed to each lower corner of the frame of each section 8, the said plate being formed with preferably integral upstanding straps 15 and 16, designed to extend along the faces of the material of the frame 8. A relatively short strap or ear 17 outstands laterally from the main body of strap 16 to enable engagement of the lower bar of the frame 8. Appropriate bolts 18, 18 are passed through straps 15, 16 and 17, and through the bars of frame 8 for securing the straps to the bars and for stiffening and strengthening the frame. The lower end of the plate 14 is bifurcated and formed with arms 19 and 20, respectively adapted to enter the notch 11 and recess 12, respectively. The lower portion of recess 12 is curved outward to form an overhanging shoulder of the material of plate 9, and the lower end portion of the arm 20 is correspondingly curved so as to extend beneath the over-hanging portion of the material of plate 9. The arm 19 is formed with an aperture 21, and the lug 13 is formed with a threaded passage registering with the aperture 21. A bolt 22 is passed loosely through the aperture 21 and threaded through the passage in lug 13. Bolt 22 terminates in a tapered end 23, engaging a substantially conical recess 24 formed in the arm 20. The recess 24 is so located with respect to the axial line of the bolt 22 that when the rounded or tapered end 23 enters the recess, it strikes the lower edge thereof and wedges the arm 20 downward, so as to draw the plate 14 down tight against the lug 13 and thus tightly bind the parts together.

In addition to this wedging action, the bolt 22 also exerts pressure on the arm 20 and pushes it out against the over-hanging portion of material of plate 9. At the same time, the bolt 22 is so proportioned as to length, that its head engages the arm 19 and clamps said arm tight against the adjacent face of lug 18. Thus, the parts are very firmly and effectively secured together in the manner susceptible of easy detachment. To detach the parts, it is only necessary to withdraw the bolts 22, there being one adjacent each end of the upper edge of each door 7, and after the bolts have been removed to swing the respective section 8 outward while withdrawing the arm 20 during such swinging movement. To replace the section 8, merely a converse operation is necessary.

It will thus be seen that when it is desired to change the nature of a vehicle from a limousine or similar closed vehicle to an open vehicle, it is only necessary to detach the sections 8, open the doors, release the latches 5, and slide out the section 6, and then the vehicle is ready for use as an open vehicle. As a matter of facility, the removed sections and windows may be stored at any appropriate place about the vehicle, as, for example, in a pocket 25 formed at the back portion of the body of the vehicle.

In Fig. 9 is illustrated a slightly modified embodiment of the structure seen in Fig. 7, wherein plate 14' is employed, which is similar in construction and function to plate 14, being provided with arms 19' and 20', adapted to extend on opposite sides of a lug 13' upstanding from a plate 9' fixed to the upper edge portion of door 7'. The plate 9' instead of being provided with an open recess or notch at one side and a closed recess at the other, is provided with a closed recess 11' at one side and a closed recess 12' at the other, the recess 11' being adapted to receive the arm 19' while the recess 12' receives the arm 20'. The recess 12' is undercut so as to form an over-hanging portion of material of plate 9', and the arm 20' is curved to under-lap said over-hanging portion. The arm 20' is proportioned relative to the dimensions of recess 12' to be allowed freedom of movement sufficient for enabling introduction and withdrawal of the arms to and from the respective recesses. A bolt 22' is extended through the inner wall of plate 9', through the arm 14' and is threaded into the lug 13'. In this construction, the snugness of the fit of the parts, and the under-lapping of the lower portion of arm 20' along the over-hanging portion of plate 9' are depended upon for providing the requisite tightness and rigidity of fit for preventing looseness or rat-

tling. The operation of the structure, so far as assemblage and demounting is concerned, is the same as that described with respect to the structure seen in the preceding figures 5 of the drawing.

It will be observed that in both Figs. 7 and 9, the outer depending arm is formed with a hook-like, lower free end which engages material equivalent of a retaining bar, 10 and in Figs. 10 to 13, inclusive, is shown a modified embodiment in which the hook is more pronounced, and the over-hanging element is distinctively a retaining bar.

Referring to the modification seen in Figs. 15 10 to 13, 7, indicates the vehicle door and 8" the supplemental section. In each upper corner of doors 7" is secured the plate 9", which is provided with an upstanding lug 13", on one side of which the plate 9" is 20 formed with the equivalent of a recess by being formed with apertures 12", 12", leaving a bar 9* extending above the lower aperture and across the upper aperture and forming the boundary for each. Each corner of section 8" is provided with a plate 14" bifurcated at its lower end, producing arms 19" and 20", adapted to extend upon opposite sides of and to receive the lug 13" therebetween. The lower end portion of 30 arm 20" is formed into a hook 20* adapted to extend through the lower recess 12" and to engage the bar 9*. The arm 19" is apertured similar to the aperture in arm 19 and a bolt 22", identical with bolt 22, is passed 35 through said aperture and threaded through the lug 13". The end of the bolt 22" is tapered or rounded off to engage a similarly rounded or tapered recess in the arm 20" for functioning as described with respect to 40 the parts seen in Fig. 7.

The operation of the structure seen in Figs. 10 to 13 being identical to that described with respect to the structure seen in Fig. 7, further statement of operation is 45 unnecessary.

Whatever the method of anchorage for the supplemental section for each door, each of the doors is provided with a bead 4' similar in structure and function to bead 4, and 50 engaged by a channel bead 4" fixed to the edge of the respective supplemental section.

While each of the plates 14 and their respective parts have been described in detail in addition to the general description of 55 each section 8, it will be perfectly apparent that in fact the several plates 14 are inherent parts of their respective sections, and likewise while plate 9 in each instance has been separately mentioned, it is in fact a part of 60 its respective door, and may be so considered for purposes of interpreting the appended claims. Furthermore, it is obvious that the hook and eye connection seen distinctly in

Fig. 11 is the same in mechanical function as the hook and eye connections seen in the 65 other figures, varying only in that the eye is open in the structure seen in Fig. 11, while closed in the other figures.

What I claim is:—

1. The combination, with a vehicle door, 70 of a supplemental section adapted to be mounted thereon, one of said parts being formed with a hook-like projection, and the other with a correspondingly shaped recess, means for locking the projection in the recess, and a second projection coöperating with and spaced from the first.

2. The combination, with a vehicle door, 75 of a supplemental section formed with a hook-like projection, and the other with a correspondingly shaped recess, means for locking the projection in the recess, and a second projection coöperating with and spaced from the first, the recessed part being formed with a lug fitting between said 80 projections, said locking means retaining the lug between the projections.

3. The combination, with a vehicle door, 85 of a supplemental section therefor, one of said parts being provided with a lug extending toward the other, and the second part being provided with arms inclosing the lug, and means extending through one of the arms and engaging the lug for locking the arms and lug together, one of the arms being formed with a hook-shaped portion under-hanging a portion of the material of the first part.

4. The combination, with a vehicle door, 100 of a demountable section therefor, the door being provided with a lug, and the section being provided with arms adapted to extend on opposite sides of and engage the lug, one of the arms being formed with a tapering recess opening toward the lug, and the other arm being formed with an aperture, and a bolt having a tapered end, the bolt being extended through the aperture and threaded through the lug and having its tapered end 105 engaging the recess, the recess being positioned and dimensioned for enabling the tapered end of the bolt in entering the recess to draw the arm along the lug in a direction for binding the demountable section tight against the lug.

5. The combination, with a vehicle door, 110 of a demountable section therefor, the door being formed with an opening and with material over-hanging a portion of the opening, and the demountable section being formed with an arm adapted to extend into the opening and curved to under-hang said over-hanging portion of the material of the door, and a bolt threaded through a portion 115 of the material of the door and engaging the arm, and pressing the same toward the

over-hanging material of the door for securing the parts together.

6. The combination, with a vehicle door, of a demountable section therefor, the door and section having a hook and eye connection, and means coöperating therewith for retaining said connection in operative condition, the said means comprising a bolt threaded through a portion of the material

of the door and engaging the hook for pressing the same toward the eye connection and securing the parts together. 10

In testimony whereof I affix my signature in presence of two witnesses.

ARTHUR J. CHAMPAGNE.
